UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 13,987, dated June 19, 1883.

Application filed May 4, 1883. Term of patent 3½ years.

To all whom it may concern:

Be it known that I, PAUL PIGNOT, of Yonkers, Winchester county, New York, have invented a new and original Design for Carpets, 5 of which the following is a specification.

The accompanying photograph illustrates my new design for carpets.

This invention relates to a new design for carpets, oil-cloths, and analogous fabrics; and 10 it consists of the new ornamentation of parts, hereinafter more fully pointed out.

In the accompanying photograph, the letter A represents a bouquet of flowers, which constitutes the main design on the carpet—in fact, 15 the only design that is here represented—said bouquet being composed of various flowers, such as tulips, roses, and the like, so arranged

with reference to their grouping and outline as to produce the peculiar effect shown. A sort of background is formed by projecting 20 sprays of flowers a, that extend from the bouquet, but are less pronounced in tone than the flowers of the bouquet, thus giving the latter the appearance of standing out prominently from the background of the carpet. 25

I claim—

The design for carpets, consisting of the bouquet A and flowers a, substantially as shown.

PAUL PIGNOT.
